HOUSING FOR A REMOTE CONTROL UNIT FOR
A TELEPHONE ANSWERING APPARATUS OR
THE LIKE

Edward M. Cappucci, Ardsley, and Arthur R. Marotta,
Westbury, N.Y., assignors to Robosonics, Inc., a cor-
poration of Delaware

Filed Nov. 17, 1965, Ser. No. 88,130

Term of patent 14 years

(Cl. D26—14)

FIG. 1

FIG. 2

FIG. 3

FIG. 4

FIG. 5

FIGURE 1 is a perspective view of one side of a housing for a remote control unit for a telephone answering apparatus or the like, showing our new design;

FIGURE 2 is a perspective view of the other side thereof;

FIGURE 3 is a top view thereof;

FIGURE 4 is an end elevational view thereof; and

FIGURE 5 is a bottom view thereof.

We claim:

The ornamental design for a housing for a remote control unit for a telephone answering apparatus or the like, substantially as shown.
